UNITED STATES PATENT OFFICE.

ROBERT T. DARRAH, OF PHILADELPHIA, PENNSYLVANIA.

REVOLVING COAL CHUTE AND CRIB.

SPECIFICATION forming part of Letters Patent No. 606,520, dated June 28, 1898.

Application filed May 10, 1897. Serial No. 635,816. (No model.)

To all whom it may concern.

Be it known that I, ROBERT T. DARRAH, of Philadelphia, in the county of Philadelphia and State of Pennsylvania, have invented certain new and useful Improvements in Revolving Coal Chutes and Cribs; and I do hereby declare the following to be a full, clear, and exact description of the invention, such as will enable others skilled in the art to which it applies to make and use the same.

This invention relates to unloading devices; and it consists, essentially, of a revolving coal chute and crib comprising adjustable parts adapted to be directed at any angle from a wagon or vehicle to which it is attached.

The invention further consists of the details of construction and arrangement of the several parts, which will be more fully hereinafter described and claimed.

20 The object of the present invention is to provide an attachment especially applicable to coal-wagons or analogous vehicles in the nature of a telescopic chute carried by a revolving crib which is attached to receive the 25 said chute when folded and be turned under the body of the wagon or vehicle to direct the run of or delivery of coal at any desired point and avoid blocking a street or thoroughfare.

In the accompanying drawings, Figure 1 is 30 a perspective view of a portion of a wagon-body, showing the improved rotatable crib attached thereto and the coal-chute extended in operative position. Fig. 2 is a detail perspective view of the crib holding the folded 35 chute therein and shown disconnected from the wagon-body. Fig. 3 is a central longitudinal vertical section through the crib and the folded chute-sections therein.

Referring to the drawings, wherein similar 40 numerals of reference are employed to indicate corresponding parts in the several views, the numeral 1 designates a wagon-body having at one end thereof a delivery-spout 2. The form of the wagon-body and of the spout 45 is immaterial, as the improved device is adapted to be applied to any form of wagon now in use, and has attached to the underside thereof a pair of parallel guides 3, with grooves 4 in the inner edges, which adjustably receive 50 the opposite ends of a supporting-bar 5. The guides 3 extend a suitable distance

beyond the end of the wagon and have braces 6 secured thereto to form a rigid structure. The supporting-bar 5 is reduced at its central portion, and has a pivot-bolt 8 rotatably mounted therein, which extends through the upper portion of a crib 9. The opposite sides of this crib are supplied with suitable pivot plates or arms 10, to which chains 11 are secured and are adapted to hold the chute in 60 closed position within the crib and also may be placed over the opposite sides of the adjacent chute-section to steady and reinforce it. The opposite sides of the wagon-body or an adjacent portion of the frame will also be provided with suitable stay-chains 12 and also with eyes 13, to which the chains 11 may be secured in holding the crib in its adjusted position. The chute in this instance is telescopic in its construction and arrangement 70 and consists of four sections 14, 15, 16, and 17. The section 14 is stationary in the crib 9 and is arranged normally at an angle of inclination, its rear or inner end being secured to the top portion of the crib, and each of the 75 sections 15, 16, and 17 have oppositely-positioned flanges 18, with slots 19 therein. The sections 14, 15, and 16 have flat-headed rivets 20 in the front portions thereof which engage the slots 19, and when the sections of the 80 chute are distended the end of one overlaps the adjacent end of the other, and when telescoped they move regularly one under the other. At the rear upper portion of the flanges, on the sections 16 and 17, upwardly-projecting inwardly-extending retention-arms 85 21 are located and hold the several sections against too much play and relieve the rivets 20 of a portion of the strain brought to bear thereon through the weight of the several sections. Attached to the front end of the chute 90 17 are adjustable loops 22, adapted to be engaged by the said chains 11 to hold the chute-sections within the crib when folded and against accidental disconnection through vibration or movement of the wagon or vehicle carrying the same. The upper part of the crib 9 is open at various points to not only lighten the structure, but to form arms 23, with a slightly-raised center for connection 95 100 with the pivot-bolt 8, and insure an easy rotation of the crib without catching or jam-

ming at any point. All the connecting rivets or bolts have the heads and ends thereof flattened, so as to prevent the formation of projections which might catch on the several parts and interfere with the desired adjustment.

The several chute-sections, as well as the crib and other parts, are preferably constructed of steel to resist wear and to be thereby reinforced against breakage by shocks and jars.

In operation the crib 9 can be turned from either side of the vehicle as far as the running-gear will permit; but the parts are so arranged through their several adjustable features that the angle of adjustment can be varied at will without interfering with any part of the wagon or vehicle. When the chute is regularly arranged in connection with the 15 end of a wagon, the supporting-bar 5 is moved outwardly in its guides and the crib turned thereon to direct the chutes to the desired point. When not in use, the chute-sections are telescopically folded into the crib and the 20 latter then adjusted under the wagon bed or body, the several parts being locked and supported during distention and inclosure by the stay-chains, as set forth.

It is obviously apparent that many minor 30 changes in the construction and arrangement of the several parts might be made and substituted for those shown and described without in the least departing from the nature or spirit of the invention.

35 Having thus described the invention, what is claimed as new is—

1. In a device of the character set forth, the combination of a revolving crib, and a telescopic coal-chute carried thereby, substantially as and for the purposes specified.
2. In combination with a wagon bed or body, a revoluble crib attached thereto, a coal-chute comprising a series of telescopic sections movable into and outward from the said

crib, and means for holding the chute in its 45 adjusted position, substantially as described.

3. In a device of the character set forth, the combination of a wagon bed or body, guides attached thereto, a supporting-bar adjustably mounted in said guides, and a crib 50 having telescopic chute-sections therein rotatably attached to the said supporting-bar, substantially as and for the purposes specified.

4. A coal-chute comprising a rotatable crib 55 a series of telescopic sections provided with opposite flanged sides having slots therein, and connecting devices carried by a part of the chute-sections and engaging the slots set forth, substantially as and for the purposes 60 specified.

5. In a device of the character set forth, the combination of a rotatable crib having a stationary chute-section mounted therein at a downward angle of inclination, and telescopic sections attached to said stationary section and to each other and adapted to telescope into said crib, substantially as and for the purposes specified.

6. In a device of the character set forth, 70 the combination of a wagon-body having stay-chains and attaching devices on parts thereof, an adjustable crib mounted in connection with said body also having stay-chains thereon, and telescopic chute-sections carried by 75 said crib and having devices at the outer end of the outermost section adapted to be engaged by portions of said stay-chains, said chute-sections being adapted to slide into said crib, substantially as and for the purposes 80 specified.

In testimony whereof I have signed this specification in the presence of two subscribing witnesses.

ROBERT T. DARAH.
